UNITED STATES PATENT OFFICE.

ARTHUR W. WADSWORTH, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE-PENDANT.

51,353.

Specification for Design.

Patented Oct. 9, 1917.

Application filed June 4, 1917. Serial No. 172,807. Term of patent 14 years.

To all whom it may concern:

Be it known that I, ARTHUR W. WADSWORTH, a citizen of the United States, residing at Fort Thomas, in the county of Campbell, in the State of Kentucky, have invented a new, original, and ornamental Design for Watchcase-Pendants, of which the following is a specification, reference being had to the accompanying drawing, forming part thereof.

In the drawing:

Figure 1 is a side elevation; and
Fig. 2 is an edge view.

I claim:

The ornamental design for a watchcase pendant, substantially as shown.

ARTHUR W. WADSWORTH.

Witnesses:

JAMES N. RAMSEY,
CLARENCE PERDEW.
